SHOE STRETCHER

James Ventola, Kansas City, Mo.

Application November 9, 1936, Serial No. 109,946

4 Claims. (Cl. 12—128.3)

My invention relates to improvements in shoe stretchers.

One of the objects of my invention is the provision of a novel shoe stretcher with which a shoe upper can be simultaneously stretched laterally and lengthwise, of which it may be stretched independently either laterally or lengthwise.

A further object of my invention is the provision of a novel shoe stretcher which is simple, cheap to make, strong, durable, not likely to get out of order, which is easy to operate, and which is efficient in its operation.

The novel features of my invention are hereinafter fully described and claimed.

In the accompanying drawing, which illustrates the preferred embodiment of my invention,

Fig. 1 is a top view, partly broken away, of my improved shoe stretcher, shown with the spreader members in the innermost position.

Fig. 2 is a section on the line 2—2 of Fig. 1.

Fig. 3 is a section on the line 3—3 of Fig. 1.

Fig. 4 is a reduced longitudinal sectional view of my improved shoe stretcher shown in operative engagement with a shoe.

Fig. 5 is an enlarged front view of the stretcher member which is used in stretching the shoe upper lengthwise.

Similar characters of reference designate similar parts in the different views.

1 designates a transverse plate which constitutes bearing means for two spreader members 2 and 3 disposed side by side and adapted for insertion into the toe portion of a shoe for widening the shoe upper rearwardly from the toe.

35 The rear ends of the spreader members 2 and 3 are respectively provided with two transverse grooves 4 in which are respectively pivotally mounted the end portions of the plate 1 to which the members 2 and 3 are pivotally connected by 40 parallel pivot pins 5, which pins comprise connecting means by which the spreader members 2 and 3 may be swung laterally outwardly in opposite directions for spreading the shoe upper laterally.

45 For so forcing the spreader members 2 and 3, there is provided a rod 6 which is rotatably mounted in and extends forwardly and rearwardly through the bearing plate 1 between the members 2 and 3.

50 Said rod 6, forwardly from the bearing plate 1, is screw threaded from its front end. A nut 7 is fitted and adapted for travel on said threaded front end portion of the rod 6, when the rod is rotated in the plate 1. For holding the rod 6 from longitudinal movement in the bearing plate

1, it has fastened on it two collars 8 and 9 respectively bearing against the front and rear edges of the plate 1.

The nut 7 is between the spreader members 2 and 3 and is mounted in two grooves 10 respectively provided in the inner sides of the members 2 and 3. The bottoms of the grooves 10 increase in depth from the front rearwardly and provide bearing surfaces 11, which diverge rearwardly from each other when the members 2 and 3 are in the inner position, shown in Fig. 1. The nut 7 is adapted to have its opposite edges respectively slidably engage the bearing surfaces 11, when the rod 6 is rotated in a direction such that the nut 7 will be moved forwardly, which direction will be clockwise, looking toward the left in Fig. 1, as the front end portion of the rod 6, as shown is threaded left handed.

When the nut 7 moves forwardly and is engaged with the bearing surfaces 11, it operates as a wedge which forces the spreader members 2 and 3 to swing outwardly at their forward ends, thus laterally stretching the shoe upper 12 at the rear of the toe and forward of the instep.

The rod 6 is provided with a handle 13 by which it may be rotated in either direction. The rod 6 between the handle 13 and the bearing plate 1 is threaded oppositely to the threaded front end portion of the rod. Such rear threaded portion has fitted and adapted for travel on it a nut 14, which, when the handle 13 is turned clockwise moves the nut 14 rearwardly.

15 designates a stretcher member having through it a vertical slot 16 which increases downwardly in diameter. The nut 14 is provided with an annular peripheral groove 17, the rear end of the nut being circular and smaller in diameter than the front end. The rear end of the nut 14 is insertable through the larger lower end of the slot 16, but is of larger diameter than the upper portion of the slot, so that when the nut 14 is inserted into the wider portion of the slot 16 and then moved upwardly to the upper end thereof, the stretcher plate or member 15 will be moved forwardly and rearwardly with the nut 14.

The stretcher member 15 is adapted to have bearing engagement with the inner front side of the heel portion of the shoe upper, as shown in Fig. 4, so that when operatively engaged with the nut 14, as shown in Figs. 1 and 4, and the handle 13 is turned clockwise, the nut 14 will be moved rearwardly thus forcing the stretcher member 15 rearwardly so as to also force rearwardly the heel portion of the shoe upper, thereby stretching the shoe upper lengthwise.

In the operation of my improved shoe stretcher, when it is desired to simultaneously spread and lengthen the shoe upper, the parts are assembled as shown in Fig. 1, with the spreader members 5 in the inner position, as shown, and the spreader members 2 and 3 are then inserted into the toe portion of the shoe, the nut 7 being disposed in the grooves 10 engaged with the bearing surfaces 11. The nut 14 is disposed on the rod 6 so as to 10 bring the stretcher member 15 against the front inner side of the heel portion of the shoe upper 12, as shown in Fig. 4.

The handle 13 of the rod 6 is then revolved clockwise, thus forcing the nut 7 forwardly and 15 the nut 14 rearwardly, whereby the spreader members 2 and 3 are swung laterally outwardly in opposite directions, thus spreading and stretching the shoe upper laterally, and the stretcher member 15 forces the heel portion of the 20 shoe upper rearwardly, thus stretching the shoe upper lengthwise.

If it is desired to spread but not lengthen the shoe upper, the stretcher plate 15 is removed from the nut 14, the latter being screwed forwardly out of contact with the shoe upper. The rod 6 is then turned so as to move the nut 7 forwardly, thus causing the spreader members 2 and 3 to laterally stretch the shoe upper.

If it is desired only to lengthen the shoe upper, 30 the nut 7 is unscrewed off the rod 6 at the front end thereof, and the nut 14, stretcher member 15, and rod 6 are operated to force the stretcher member 15 rearwardly, thus stretching the shoe upper lengthwise.

35 Various modifications of my invention, within the scope of the appended claims, may be made without departing from the spirit of my invention.

What I claim is:—

40 1. In a shoe stretcher, bearing means, two spreader members, means connecting said members to said bearing means by which they are permitted to move outwardly in opposite directions to spread a shoe, a rod rotatable in and held from longitudinal movement by said bearing means and having two oppositely threaded portions, two nuts respectively fitted and adapted for travel on said portions when said rod is rotated relatively to said nuts, one of said nuts being between and adapted, when moved in one direction, to engage and force said members outwardly in opposite directions, and a stretcher member engageable with and movable forwardly and rearwardly by the other nut and adapted to engage and force rearwardly the heel portion of the shoe upper.

45 2. In a shoe stretcher, bearing means, two spreader members, means connecting said members to said bearing means by which they can move laterally in opposite directions to spread a shoe, a rod rotatable in and held from longitudinal movement by said bearing means and hav-

ing two oppositely threaded portions, two nuts respectively fitted and adapted for travel on said portions when said rod is rotated relatively to said nuts, one of said nuts being between and adapted, when moved in one direction, to engage and force said members laterally outwardly in opposite directions, and a stretcher member engageable with and movable forwardly and rearwardly by the other nut and adapted to engage and force rearwardly the heel portion of the shoe upper, said rod extending through said stretcher member and having a handle at its rear end by which it is rotated.

3. In a shoe stretcher, bearing means, two spreader members pivoted adjacent to their rear ends to said bearing means so as to be adapted to be swung outwardly laterally from an inner position and having respectively at their inner sides two bearing surfaces which diverge from each other when said members are in said inner position, a rod rotatable in and held from longitudinal movement by said bearing means and having two oppositely threaded portions, two nuts respectively fitted and adapted for travel on said portions when said rod is rotated relatively to said nuts, one of said nuts being between and having sliding engagement with said bearing surfaces and adapted, when moved in one direction, to force said members laterally outwardly to spread the shoe upper, and a stretcher member engageable with and movable forwardly and rearwardly by the other nut and adapted to engage and force rearwardly the heel portion of the shoe upper, said rod extending through said stretcher member and having a handle at its rear end by which it is rotated.

4. In a shoe stretcher, two spreader members, bearing means, means connecting said members to said bearing means by which they are permitted to move outwardly laterally in opposite directions from an inner position, a rod rotatable in and held from longitudinal movement by said bearing means and having two oppositely threaded portions, one of which extends to the front end of said rod, a nut fitted and adapted for travel on and to be unscrewed from said last named portion, another nut fitted and adapted for travel on the other of said threaded portions, said first named nut being between and adapted, when moved in one direction, to engage and force said spreader members laterally outwardly in opposite directions to spread a shoe upper adapted to be engaged by said members, and a stretcher member having means for being releasably engaged and moved forwardly and rearwardly by said second named nut and adapted to engage and force rearwardly the heel portion of the shoe upper, said rod extending through said stretcher member and adapted to be extended over the heel portion of the shoe and having at its rear end a handle by which it is rotated.

JAMES VENTOLA.
